UNITED STATES PATENT OFFICE

2,171,836

HAIR CURLER

Frances H. McCardell, Selma, Ala.

Application September 26, 1938, Serial No. 231,798

2 Claims. (Cl. 132—43)

The present invention relates to hair curlers of a type embodying an elongated flexible member upon which the hair is adapted to be rolled, and has for its primary object to provide a cloth pad secured to the curler and embodying a double layer of material between which the ends of a strand of hair are positioned in order that the same will be held smoothly and rolled upon the curler without permitting any ragged protruding ends.

A further object is to provide a curler of this character of simple and practical construction, which is efficient and reliable in use and otherwise well adapted for the purposes for which the same is intended.

Other objects and advantages reside in the details of construction as more fully hereinafter described and claimed, reference being had to the accompanying drawing forming part hereof, wherein like numerals refer to like parts throughout, and in which—

Figure 1 is a side elevational view, and

Figure 2 is a transverse sectional view taken substantially on a line 2—2 of Figure 1.

Referring now to the drawing in detail, the numeral 5 designates a flexible curler of conventional construction which embodies a leather sheath 6 having a flexible wire core 7, the sheath being constructed of a single piece of leather and having its longitudinal edges secured together by stitching 8.

The stitching 8 also passes through the intermediate portion of a cloth pad 9 which is folded upon itself, as clearly shown in Figure 2 of the

drawing, to provide double layers of cloth material between when the ends of the hair 10 may be inserted.

Accordingly, in the operation of the device, with the ends of the hair positioned between the cloth pad 9, as illustrated in Figure 2 of the drawing, the ends of the hair will be held smoothly and in a substantially uniform plane so that no protruding ends of the hair will occur when the hair and the pad are rolled about the curler 5 in a manner as will be apparent.

It is believed the details of construction will be readily understood from the foregoing without further detailed explanation.

Having thus described the invention, what I claim is—

1. A hair curler comprising an elongated flexible curler rod including a flat longitudinal edge and a cloth pad folded upon itself and secured along its line of fold to the flat edge of the rod to provide a double layer of cloth having free end and side edges and between which the ends of the hair to be curled are adapted for positioning for rolling about the curler.

2. A hair curler comprising an elongated member of flexible material having one of its longitudinal edges formed with an opening, a cloth pad folded upon itself and between which the ends of the hair to be curled are adapted for positioning, and stitching securing the pad along its line of fold to the curler and also for securing the open longitudinal edges of the curler together.
